UNITED STATES PATENT OFFICE.

GEORGE V. STRAHAN, OF NEWARK, NEW JERSEY.

DESIGN FOR A WALL-PLATE FOR LIGHTING-FIXTURES.

54,289.

Specification for Design.

Patented Dec. 9, 1919.

Application filed June 6, 1919. Serial No. 302,352. Term of patent 7 years.

To all whom it may concern:

Be it known that I, GEORGE V. STRAHAN, a citizen of the United States of America, and a resident of the city of Newark, in the county of Essex and State of New Jersey, have invented a new, original, and ornamental Design for a Wall-Plate for Lighting-Fixtures, of which the following description, in connection with the accompanying drawing, is a specification.

The single figure of the drawings is a front elevation of a wall plate for lighting fixtures showing my design.

I claim as my invention:

The ornamental design for a wall plate for lighting fixtures, as shown.

GEORGE V. STRAHAN.

Correction in Design Letters Patent No.
54,289.

It is hereby certified that Letters Patent No. 54,289, granted December 9, 1919, upon the application of George V. Strahan, of Newark, New Jersey, for a "Design for a Wall-Plate for Lighting-Fixtures," were erroneously issued to the inventor, said Strahan, whereas said Letters Patent should have been issued to *Mitchell Vance Co., Inc., of New York, N. Y., a corporation of New York*, as shown by the records of assignments in this office; and that the said Letters Patent should be read with this correction therein that the same may conform to the record of the case in the Patent Office.

Signed and sealed this 6th day of January, A. D., 1920.

[SEAL.]

M. H. COULSTON,

Acting Commissioner of Patents.
